UNITED STATES PATENT OFFICE

CARL GEORG MUNTERS, OF STOCKHOLM, SWEDEN, ASSIGNOR TO ELECTROLUX SERVEL CORPORATION, OF NEW YORK, N. Y., A CORPORATION OF DELAWARE

REFRIGERATOR

Application filed July 19, 1929, Serial No. 379,351, and in Sweden July 21, 1928.

The present invention relates to a refrigerator cabinet, particularly for domestic purposes, provided with an absorption refrigerating apparatus, and is characterized by the combination of a heated compartment with said refrigerator cabinet in such a manner that this compartment is heated by means of the same medium which operates the refrigerating apparatus.

10 Absorption refrigerating apparatus combined with refrigerator cabinets are frequently operated by means of gas heating, whereby the exhaust gases escaping from the heating device of the apparatus have such a 15 high temperature, for example 140-150° C., that the same advantageously can be used for the heating of a compartment of known type, for instance for keeping victuals warm. The 20 heated compartment, the inner volume of which for ordinary domestic purposes is relatively small as compared to that of the refrigerator cabinet, is preferably placed above the latter as will appear from the embodiment of the invention illustrated in the accompanying drawing.

Fig. 1 is a cross-sectional view of an embodiment of my invention; and

30 Fig. 2 is a cross-sectional view taken on the lines 2-2 of Fig. 1.

On this drawing a refrigerator cabinet combined with a heated compartment in accordance with the invention is shown in longitudinal section. In the drawing reference 35 character *a* designates the refrigerator cabinet, on the back side of which an exclusively heat operated continuously working absorption refrigerating apparatus *b* is arranged, the evaporator *c* of which extends into the 40 refrigerator cabinet. The refrigerating apparatus is operated by continuous gas heating of the generator in the usual way and the exhaust gases escape from the heating device of the apparatus through a conduit *d* leading 45 to another heating device provided in the compartment *e*, which has a considerably smaller volume than the refrigerator cabinet *a*, which heating device in the illustrated embodiment consists of an extension of said conduit *d*. In order to facilitate a heat transfer

between the exhaust gases and the air in the compartment *e*, that part of conduit *d* arranged inside the compartment may be provided with fins of known type, or be formed in such manner that a sufficiently large heat transfer surface is obtained. Both compartments *a* and *e* are well heat insulated and their interiors are accessible through doors *f* and *g* arranged on the front sides of the boxes.

In order to control the temperature within compartment *e* a second flue 10 is provided which communicates with flue *d* at a point in the latter flue below or in the lower part of compartment *e*. Flue 10 extends substantially entirely outside of compartment *e*. In order to distribute the heated flue gases between flues *d* and 10 so as to regulate the temperature within the compartment, a valve member 11 is provided. Valve 11 is pivoted at the juncture of flues *d* and 10 and is so arranged that in one extreme position it completely closes flue 10 while in the other extreme position it completely closes flue *d*. Valve 11 is mounted on a pivot 12 which extends outside of the flue and has secured to its outer end a crank 13. Crank 13 is provided with a slot 14 which engages a pin 15 mounted on a rod 16. Rod 16 extends within a cylinder 17 where it is secured to a piston which is arranged to be moved within the cylinder. The other end of the cylinder 17 communicates with a conduit 18 which extends to a thermostatic element 19 located in any desired place within compartment *e*.

If the temperature within compartment *e* rises above a predetermined point, fluid within thermostatic element 19 expands and passes through conduit 18 to cylinder 17 where it acts upon the piston therein to move rod 16 downwardly, as viewed in Fig. 2. This movement of rod 16 causes crank 13 to turn in a clockwise direction which causes valve 11 to likewise turn in a clockwise direction and thus allow the passage of flue gases from flue *d* into flue 10, while at the same time preventing to a greater or lesser degree the passage of flue gases directly through flue *d*. If the temperature has become sufficiently high, valve member 11 will be turned 10a

to a horizontal position and thus cause the passage of all the flue gases through flue 10. Inasmuch as practically the entire length of flue 10 is outside of compartment *e*, the compartment

- 5 will not be heated by the passage of flue gases therethrough. Upon a reduction of temperature in compartment *e* valve 11 will tend to allow more of the gases to pass through flue *d* and less through flue 10.
 10 Thus valve member 11 functions to distribute the flue gases between the two flues in such a manner as to obtain a constant temperature in compartment *e*.

Under certain circumstances, for instance 15 if the refrigerating apparatus is heated by a medium of high temperature coming from a heat-source separate from said apparatus, it may be suitable first to conduct this medium or a part thereof through the heating 20 device of the heated compartment and thereupon to the refrigerating apparatus.

While I have shown and described a more or less specific embodiment of my invention, it is to be understood that I am to be 25 limited only by the appended claims viewed in the light of the prior art.

Having thus described my invention, what I claim is:

1. In combination, a refrigerator cabinet 30 having a compartment to be cooled, an absorption refrigerating apparatus comprising a generator and an evaporator, said evaporator being located in said compartment, walls forming an insulated compartment to be 35 heated situated above the compartment to be cooled and adapted to receive food, means for continuously heating said generator by combustion, a flue for conveying products of combustion from said generator, said flue 40 passing outside of said compartment to be cooled and within said compartment to be heated, and means providing extended heat transfer surface on said flue within the compartment to be heated.
 45 2. In combination, a refrigerator cabinet having a compartment to be cooled, an absorption refrigerating apparatus comprising a generator and an evaporator, said evaporator being located in said compartment, walls 50 forming an insulated compartment to be heated, means for continuously heating said generator by combustion and means for indirectly heating said last mentioned compartment with waste heat from said generator.
 55 3. In combination, a refrigerator cabinet having a compartment to be cooled, an absorption refrigerating apparatus comprising a generator and an evaporator, said evaporator being located in said compartment, walls 60 forming an insulated compartment to be heated situated above the compartment to be cooled and adapted to receive food, means for continuously heating said generator by 65 combustion and a flue for conveying products

of combustion from said generator, said flue passing outside of said compartment to be cooled and within said compartment to be heated.

4. In combination, a refrigerator cabinet 70 having a compartment to be cooled, an absorption refrigerating apparatus comprising a generator and an evaporator, said evaporator being located in said compartment, walls forming an insulated compartment to be 75 heated situated above the compartment to be cooled and adapted to receive food, means for continuously heating said generator, means for heating the compartment to be heated with waste heat from said generator 80 and temperature responsive means in the last mentioned compartment operative to maintain a constant temperature therein.

5. In combination, a refrigerator cabinet 85 having a compartment to be cooled, an absorption refrigerating apparatus comprising a generator and an evaporator, said evaporator being located in said compartment, walls forming an insulated compartment to be 90 heated situated above the compartment to be cooled and adapted to receive food, means for continuously heating said generator, a flue for conveying waste heat from said generator, said flue passing outside of said compartment to be cooled and within said compartment to be heated, a second flue communicating with said first flue and arranged to 95 pass substantially entirely outside of said compartment to be heated and valve means for distributing flow between said flues. 100

6. In combination, a refrigerator cabinet 105 having a compartment to be cooled, an absorption refrigerating apparatus comprising a generator and an evaporator, said evaporator being located in said compartment, walls forming an insulated compartment to be 110 heated situated above the compartment to be cooled and adapted to receive food, means for continuously heating said generator, a flue for conveying waste heat from said generator, said flue passing outside of said compartment to be cooled and within said compartment to be heated, a second flue communicating with said first flue and arranged to 115 pass substantially entirely outside of said compartment to be heated, valve means for distributing flow between said flues and temperature responsive means located in said compartment to be heated operative to control said valve. 120

In testimony whereof I have hereunto affixed my signature.

CARL GEORG MUNTERS.
